UNITED STATES PATENT OFFICE.

GORDON E. ROEDDING, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH.

Application filed July 28, 1926. Serial No. 125,406.

The present invention relates to latches for the doors of refrigerators and the like; and its object is to provide a latch having improved means for yieldingly holding the 5 latching bolt in certain positions, and, in certain movements of the bolt, urging the same into another of its positions; and further, to provide a latch having such means and adapted to be mounted on a door swing- 10 ably carried at either of its opposite sides; and further, to provide improved means for locking the latching bolt against retraction.

These and any other objects hereinafter appearing are attained by, and the invention finds preferable embodiment in, the structure hereinafter particularly described in the body of this specification and illustrated by the accompanying drawings, in which:—

20 Figure 1 is a front view of a latch and its keeper element;

Figure 2 is an inner side view of the latch showing the bolt in latching position;

25 Figure 3 is a like view of the same, but showing the bolt in a retracted position;

Figure 4 is a horizontal sectional view of the same taken on line 4—4 of Figure 2;

30 Figure 5 is a left hand side view of the latch and its keeper element, showing the door member on which the latch is mounted approaching closed position; and

Figure 6 is a view of one of the bolt's actuating springs.

In the embodiment of the invention illustrated by the accompanying drawings, a latch is shown mounted on the closure member 1 of a door, its keeper member 2 being mounted on the jamb or frame member 3 of the door. In Figure 1, the latch is shown 35 mounted on a closure member hinged at its right hand side, but the same latch may be mounted on a closure member hinged at its opposite or left hand side. This latch comprises a latching bolt 4 swingably carried in 40 a casing 6, a portion 7 of the bolt extending through a slot 8 in the casing and being adapted to latchingly engage in the keeper or recess 9 in the element 2 to hold the closure member 1 shut, said portion 7 being desirably provided with an anti-friction roll 10. This latching bolt may be swung by hand by any suitable means or part thereof; in the illustrated construction however it is swung by its handle arm 11 extending 45 through a slot 12 in the casing.

In the illustrated latch, capable of being mounted on the right hand side or on the left hand side of a closure member, the bolt 4 has portions 13, 14 spaced apart in the bolt's transverse direction. This latching bolt is a "floating" element slidably bearing between the opposite sides 17, 18 of the slots 8 and 12. These portions 13, 14 are adapted to abut on the inner surface 19 of the casing adjacent the slot 12 in the latching position of the bolt as seen in Figure 2; but, when the outer portion 7 of the bolt is moved upwardly from latching position, the portion 13 of the bolt turns on said surface 19, while the other portion 14 of the bolt 70 moves away from said surface as seen in Figure 3; and in case the latch is mounted on a door closure hinged at its opposite or left hand side, the swinging of the bolt in the opposite direction to retracted position 75 causes the bolt's portion 14 to turn on said surface 19 and the bolt's portion 13 to move away from said surface.

Means are provided for yieldingly holding the bolt 4 in any of its positions, and at a 80 point in its movement toward any of its positions, urging the same to that position. Such means comprise a pair of U-shaped springs 20, 21 whose ends 22, 23 are rockably mounted at 24, 25 on the casing and at 85 26, 27 on the bolt adjacent its said portions 13, 14 respectively. These springs are under compression, so that they yieldingly hold the bolt in latching position seen in Figure 2. When the handle arm 11 is moved downwardly to swing the bolt 4 to the retracted position shown in Figure 3, the portion 13 of the bolt turns and slides downwardly on the surface 19 under the expansive urge of the spring 20, while the bolt's other portion 90 14 moves away from said surface, further compressing the spring 21, until the end 23 of said spring is carried past a direct line between the mounting point 25 of the spring 21 and the bearing of the portion 13 on the surface 19, whereupon this spring 21 expanding suddenly moves the bolt to the retracted position seen in Figure 3, the expanding of the other spring 20 contributing 95 to this action. When the bolt is swung from said retracted position the action of these springs, when said line is crossed, suddenly returns the bolt to latching position seen in Figure 2. It is evident that in case the latch is mounted on the opposite side of a 100 110

closure member, the action of the two springs is interchanged, the spring 20 acting as does spring 21 and the spring 21 acting as does spring 20 in the case above described.

A lock is provided for locking the bolt in latching position, comprising a tumbler 30 mounted at 31 pivotally on the bolt and having extensions 32 and 33. When the bolt is 10 in latching position, a key of common form (not shown) may be inserted into the key-hole 34 and turned sufficiently to engage the under side of the tumbler's arm 35 and turn the tumbler from its position shown in Figures 2 and 3 to a position wherein the extremity of its upper extension 32 engages the stop 36 on the casing and thus locks the bolt from being swung to the retracted position shown in Figure 3. The key may then 20 be turned back and withdrawn.

When the latch is mounted on the opposite side of a door closure, the tumbler may be turned by the key to a position wherein the extremity of its other extension 33 abuts 25 the opposite stop 37 and holds the bolt against unlatching. A spring 38 yieldingly holds the tumbler in either locking position, the tumbler at its side 39 or 40 as the case may be, sliding along this spring in the 30 swinging movement of the bolt. It is evident that this locking means is operable in the same manner in connection with any latching bolt movable in opposite directions from latching position and adapted for 35 mounting on a door closure hinged at either side.

The invention being intended to be pointed out in the claims, is not to be limited to or by details of construction of the particular 40 embodiment thereof illustrated by the drawings or hereinbefore described.

I claim:

1. In combination with a keeper therefor, a latch comprising: a bolt carried by a door member swingably to latching position and to retracted position and having portions spaced apart in the bolt's transverse direction, said member having a surface on which one of said portions turns in the bolt's swinging movement; a pair of springs pressing said portions respectively to yieldingly hold the bolt in its latching position, at least one of the springs at a point in the bolt's movement toward any one of its said positions urging the same to that position, and at least one of the springs urging one of said portions into turning engagement with said surface in the bolt's swinging movement.

2. In combination with a keeper therefor, a latch comprising: a bolt carried by a door member swingably to latching position and to retracted position and having portions spaced apart in the bolt's transverse direction, said member having a surface on which 60 one of said portions turns in the bolt's swing-

ing movement; a pair of springs having their ends pivotally connected with said member and with the bolt adjacent its said portions respectively and pressing said portions respectively to yieldingly hold the bolt in its 70 latching position, at least one of the springs at a point in the bolt's movement toward any one of its said positions urging the same to that position and at least one of the springs urging one of said portions into turning engagement with said surface in the bolt's 75 swinging movement.

3. In combination with a keeper therefor, a latch comprising: a bolt carried by a door member swingably to latching position and 80 in either direction therefrom to a retracted position and having portions spaced apart in the bolt's transverse direction, said member having a surface on which one of said portions turns in the bolt's movement to 85 and from one of its retracted positions and the other of said portions turns in the bolt's movement to and from the other of its retracted positions; a pair of springs pressing said portions respectively to yieldingly hold the bolt in its latching position, at least one of the springs at a point in the bolt's movement toward any of its said positions urging the same to that position, and at least one of the springs urging one of said portions into 90 turning engagement with said surface in the bolt's swinging movement.

4. In combination with a keeper therefor, a latch comprising: a bolt carried by a door member swingably to latching position and to retracted position; a stop carried by said member; a lock comprising a tumbler turnable on the bolt to a position engaging the stop to hold the bolt in latching position and adapted to be key-turned to a position disengaging the stop; a spring on which the tumbler slides in the bolt's movement yieldingly holding the tumbler in its stop-engaging 100 position.

5. In combination with a keeper therefor, a latch comprising: a bolt carried by a door member swingably to latching position and in either direction therefrom to a retracted position; stops carried by said member on the opposite sides respectively of the bolt; a lock 110 comprising a tumbler turnable on the bolt to a position engaging one of the stops to hold the bolt against movement in one direction to retracted position and turnable on the bolt to another position engaging the other stop 115 to hold the bolt against movement in the other direction to retracted position; a spring yieldingly holding the tumbler in either of its stop-engaging positions.

6. In combination with a keeper therefor, a latch comprising: a bolt carried by a door member swingably to latching position and to retracted position and having portions spaced apart in the bolt's transverse direction, said member having a 120 transverse direction, said member having a 125

surface on which one of said portions turns and slides in the bolt's swinging movement; a pair of springs pressing said portions respectively to yieldingly hold the bolt in its latching position, one of the springs urging one of said portions into turning and sliding engagement with said surface in the bolt's swinging movement and both springs at a point in the bolt's swinging movement toward one of its said positions urging the same to that position.

In testimony whereof I have hereunto set my hand at Grand Rapids, Michigan, this 24th day of July, 1926.

GORDON E. ROEDDING.
